COLD CONTROL FOR REFRIGERATING UNITS

Harold F. MacGrath, Detroit, Mich., assignor to
Seeger Refrigerator Company, St. Paul, Minn.,
a corporation of Minnesota

Application January 9, 1930, Serial No. 419,507

2 Claims. (Cl. 62—103)

This invention relates to a cold control for refrigerating units and is designed to increase the freezing efficiency of the refrigerating unit. In the making of ice with a refrigerating unit in 5 mechanical refrigerators where a refrigerating unit is employed it is often desirable to increase the efficiency of the refrigerating unit so that the ice may be made more rapidly by the same, such as the making of the ice cubes in the trays 10 provided. I have arranged a simple and effective means adaptable to any refrigerating unit which does not interfere with the ordinary structure of the unit or place any additional burden upon the same, but operates to confine the unit within a 15 closure, so as to speak, and prevents the circulation which would ordinarily take place about the unit through the entire refrigerator from affecting the unit, thus increasing the efficiency very quickly so that the unit may operate to freeze ice 20 in a remarkably short time.

A feature resides in means of confining the refrigerating unit within a small space which materially increases the efficiency so that the refrigerating unit can operate to freeze ice, desserts or other materials within said space rapidly.

A further feature of the invention resides in means for closing the refrigerating unit into a compartment which is confined and thus increase 30 the efficiency for the purpose of more rapidly freezing ice or desserts by the refrigerating unit.

The invention further includes a shutter means which may be placed close to the unit at the bottom and side thereof so as to confine the unit 35 within a compartment and prevent circulation from the unit to the remainder of the ice box wherein the unit is placed, thus increasing the freezing efficiency of the unit without changing the operating means and control thereof.

It is also a feature to provide means wherein the drain pan or receptacle associated with the refrigerating unit may be positioned outside of the compartment ordinarily containing the refrigerating unit, and my air circulating control 40 about the unit, or the drain pan may be placed within the compartment and the air shutter or control for the circulation about the unit positioned outside of the drain pan so as to confine the drain pan within the same compartment 45 wherein the refrigerating unit is confined.

These features with other objects and details will be more fully and clearly set forth in the specification and claims.

In the drawings forming part of this specification:

Figure 1 illustrates a partial detail of a refrigerator showing my cold control associated with the refrigerating unit of the refrigerator.

Figure 2 is a similar front view to Figure 1, showing a detail of a refrigerator with a refrigerating unit and my cold control associated therewith with shutter means at the top and bottom of the refrigerating unit compartment.

Figure 3 is a section on the line 3—3 of Figure 2.

Figure 4 is a front detail of a portion of a refrigerator, showing the refrigerating unit with my cold control associated therewith and wherein the drain pan for the refrigerating unit is confined within the refrigerating unit compartment.

In the drawings the refrigerator A is illustrated diagrammatically and only a portion of the same being illustrated to indicate the position of the refrigerating unit B which is positioned in the refrigerating compartment 10 of the refrigerator A. The refrigerating unit B may be of any suitable type, such as are used with electrically operated refrigerators and wherein the refrigerating unit B operates to provide the refrigerant for the refrigerator A to supply the necessary means of refrigerating the inner compartment of the refrigerator A.

My cold control C is of a simple structure, being positioned beneath the refrigerating unit B and having an inwardly inclined tray-like member 11 which is adapted to direct any moisture from the unit B when the unit is defrigerated, into the removable drain pan 12 which is positioned directly below the cold control C. The cold control C is provided with a slideable shutter 14 in the bottom of the same which operates by engaging the front lip 15 and moving the shutter so that it will open or close the opening 16 in the bottom of the tray 11.

The cold control C is simple to operate and being positioned near the refrigerating unit B when the shutter 14 is operated to close the opening 16, the refrigerating unit B is confined within the compartment 10 to the extent of retarding the circulation of cold coming off of the refrigerating unit B and preventing the cold air from circulating down into the food compartments 18 of the refrigerator wherein the shelves 19 are positioned, and thus the refrigerating unit B will operate to quickly freeze ice within the refrigerating unit trays 20. It is not necessary to change the operation or to increase the working load of the refrigerating unit B by means of my cold control and the operation is simple in that it is only necessary to close the shutter 14. The refrigerating unit B

ordinarily operates with the shutter 14 open so that the cold air may pass downward through the openings 16 and circulate through the food compartments 18 of the refrigerator in the ordinary manner. However, when the shutter 14 is closed the same being positioned directly below the unit B, the refrigerating unit B becomes more efficient to operate in the freezing of ice in the trays 20 and thus accomplishing a desired result in a much shorter period than where the circulation is free to pass over the unit B into the entire refrigerator A.

My cold control C may also be operated with the supplemental cold control C' which constitutes a series of shutters positioned in the side wall 21 of the refrigerating unit compartment 10 operating as movable louvers which may be opened or closed to shut off the circulation into the compartment 10 and thus increase the efficiency in the matter of freezing ice in the trays 20 of the refrigerating unit. This auxiliary control C' further increases the efficiency of the refrigerating unit B and my cold control C may be operated with or without this auxiliary cold control C'. The shutting off of the circulation by the cold control C directly below the refrigerating unit B materially increases the freezing action of the ice within the trays 20. To use the auxiliary cold control C' in conjunction with the cold control C tends to increase the efficiency even to a greater extent and thus by means of my cold control means associated with a refrigerating unit and the formation of a refrigerator in this manner provides a means of easily and simply controlling the matter of more quickly freezing ice in the trays 20.

In Figure 4 I have illustrated the drain tray 12 positioned entirely within the unit compartment 10 and the cold control shutter C is positioned below the tray 12. The upper auxiliary shutter C' is in a slideable form instead of the louver form as in Figures 2 and 3, however, the functions and operations are identical in this structure as in those heretofore described. My cold control accomplishes a long desired resultant because where refrigerating units, such as B, are used in home refrigerators or in other places where the refrigerating unit B is equipped with ice trays, such as 20, it is often desirable to freeze ice in these trays as rapidly as possible and to accomplish this my cold control operates very effectively. The cold control C can be easily operated and when the same is operated to freeze

ice in the trays 20 it can be opened and the refrigeration in the refrigerator A continues in a normal manner. Where the single control C is used as in Figure 1, below the refrigerating unit B, the circulation is not entirely shut off from the remainder or food compartments 18 of the refrigerator A, and even though the housewife should forget to open the cold control shutter 14, no material damage would be done to the food in the compartments 18 such as will take place in present cold controls for refrigerating units which, when forgotten to be readjusted, will freeze everything in the refrigerator hard as ice, and thus such a control is detrimental and undesirable. My cold control C overcomes these undesirable features and if only the single control C is used below the unit sufficient refrigeration will escape to the compartments 18 in the food chambers of the refrigerator A to ordinarily keep the food from spoiling until the housewife again opens the shutter 14.

It is apparent that the shutter 14 may be opened or closed entirely or may be adjusted to only partially close off the openings 16 in the tray portion 11 so that the shutter may be adjusted according to the desire of the user of the refrigerator A.

In accordance with the patent statutes I have described the principles of operation of my cold control and while I have set forth and illustrated certain forms and construction thereof, I desire to have it understood that the same is only suggestive of a means of carrying out the principles of my invention and it is obvious that other formations and adaptations may be employed without departing from the purpose and intent of the invention.

I claim:

1. A refrigerator including, a refrigerator unit, a compartment for enclosing the same, an inwardly inclined tray-like member at the bottom of said compartment, a perforated bottom in said tray-like member, means for adjustably closing said perforations, and means for catching moisture passing through said perforations.

2. A refrigerator including, a refrigerator unit, a compartment for enclosing said unit having side walls, an inwardly inclined tray secured to the bottom of said side walls, a perforated bottom on said tray, means for adjustably closing said perforations, and air deflector means positioned immediate beneath said bottom.

HAROLD F. MACGRATH.
